TALKING DEVICE

Howard J. Whelan, Baltimore, and Louis T. Clark, Ellicott City, Md.

Application November 4, 1932, Serial No. 641,294

1 Claim. (Cl. 274—1)

This invention refers to talking and musical instruments, and more particularly to a device for intoning special wording in a continuous manner, and operated as a hand instrument and general portable purposes.

It has among its objects to provide a device of this class that may be adapted for special purposes, and particularly to accentuate certain expressions that will influence the hearer.

Another object is to have the device adaptable for using several different expressions, which can be adjusted at will to be used.

A further object is to have the device self containable and utilize new arrangements for developing using expressions, or tones or whatever may be brought into play.

Many other objects will become apparent as the invention is more fully set forth.

While many devices have been developed and used for recording and repeating sounds and words, such devices are in general cumbersome and undesirable for portable handling. This device is simple in construction, and light in weight, and combines in a few parts, all that is necessary for bringing about the sounds and expressions predetermined. It does not use removable records and the distinctive mechanism that is required in a graphophone. It is preferably operated by hand, and performs a special function such as repeating a slogan, advertising a subject, expressing a pleasantry, and otherwise filling some particular purpose which meets a special situation, and which it is desired to emphasize in the mind of the hearer.

In the drawing, which illustrates by way of example an embodiment of this invention:

Figure 1 is a perspective view of a voice box embodying this invention,

Figure 2 is a sectional view showing the recorder and speaker used in this embodiment.

Similar reference characters refer to similar parts throughout the drawing.

In the construction, 1 represents a box, which is preferably round and cylindrical, that has an opening 2, in which a special speaker cone 4, is located and faces outwardly in the box as indicated. The speaker cone is made of a prepared paper metal or silk or suitable material that gives it a desirable stiffness and makes it a suitable diaphragm. It has a spindle 5 attached at its apex and secured thereto with a suitable conical nut 6. The spindle is provided with a needle 7 that is adapted to engage on the recoding wheel 8 on its edge 9 which is provided with sound marks 10. This wheel has a hub 11 and is mounted on a shaft 12, which is suitably mounted in

the box. A slight sidewise movement is permitted with the shaft in the box, in order to permit more than one slogan to be provided on the recoding wheel. In order to provide a recoding wheel that will not require the usual type of removable records used on talking machines, this device is provided with special features of recoding, that have been developed in bringing out this invention. The manner of making this recoding wheel, as it is called, is in one case to make it of aluminum, and produce the codes thereon. It is also found feasible to make the wheel of rubber with its edges soft when recoding and then hardened with a cooling process; also to use plaster of Paris with a coating of copper or copper plated to provide a more permanent using; and also to use a lead wheel with a coating of copper or harder metal for wearing provision.

The shaft is provided with a handle 13 for manual operation, which for lightness and general use is preferred to providing a motor of any kind, although same might be used and the handle provided for winding same up.

In its operation the device is operated by turning the handle, and the edge of the wheel with its code marks engage with the needle, and the needle transmits the vibrations directly to the cone speaker and gives out the tones provided on the wheel edge. This is repeated, as many times as the wheel is rotated. The cone by reason of its construction readily transmits the sounds in a clear and distinct manner.

If more than one slogan is required, the extra expression is provided on the wheel edge by the side of the other, and the shaft is moved to bring it into registry when about to be used.

While but one form of construction is shown in the drawing, it is not desired to limit this application for patent to this particular, or in any other way, otherwise than limited by the prior art, as it is appreciated that other constructions could be made that would use the same principles and come within the scope of the appended claim.

Having thus described the invention, what is claimed is:

In a manually operated phonograph, the combination of a box of hollow cylindrical form having an opening in one end thereof, a diaphragm disposed in the said opening, a stylus attached to said diaphragm, a shaft extending diametrically through said cylindrical box, a handle for turning said shaft, a record mounted on the shaft within the box, said record being engaged by said stylus to reproduce sound.
